UNITED STATES PATENT OFFICE.

FRANCIS JAY LYNCH, OF BLOOMFIELD, NEW JERSEY.

RECEPTACLE.

Original application filed May 6, 1921, Serial No. 467,415. Divided and this application filed December 3, 1921. Serial No. 519,623.

To all whom it may concern:

Be it known that I, FRANCIS JAY LYNCH, a citizen of the United States, and resident of Bloomfield, in the county of Essex and 5 State of New Jersey, have invented a new and Improved Receptacle, of which the following is a full, clear, and exact description.

My invention relates to a receptacle, and 10 is a division over my co-pending application number 467,415, filed May 6, 1921.

It is an object of this invention to provide a receptacle capable of being manufactured at an extremely nominal figure, which receptacle is particularly adapted for use in 15 connection with the shipment and storage of photographic cartridges, or spools, and similar articles.

It is well appreciated in connection with 20 articles of the class referred to that considerable difficulty has been experienced in shipment, incident to the fact that atmospheric conditions, and moisture would readily spoil the same. Thus it has been necessary to either ship members of this nature 25 in usual packing, in which the same were liable to become damaged, or to utilize a relatively expensive container, and the difficulties of this latter expedient have been 30 pointed out in my co-pending application.

Thus my present invention aims to provide a receptacle particularly adapted for use in the association mentioned, but not necessarily limited to this particular use, 35 by means of which a container will be provided, which shall virtually preclude any damage occurring to its contents incident to atmospheric conditions or to moisture.

Another object of this invention is the 40 construction of a device of the class specified in which the cartridge or similar element is grasped by, and retained within the receptacle in such a manner as to prevent any movement of the shipped article 45 with respect to the container, thus reducing the liability of damage to both of these elements.

A still further object of this invention is the construction of a receptacle which 50 will be strengthened adjacent those points at which it is subjected to a maximum amount of wear.

Among further objects of this invention is the provision of a receptacle embodying 55 the foregoing qualities, but which may readily be opened by a user, and which re-

ceptacle during manufacture and packing will readily lend itself to use in connection with automatic machinery, and

Still further objects of this invention will 60 become apparent in the annexed specification taken in connection with the drawings, which latter illustrate one practical embodiment thereof, and in which;

Figure 1 is a sectional side view of a 65 receptacle embodying my improved construction and showing an article within the same.

Figures 2, 3 and 4 are enlarged fragmentary sectional views of the upper portion 70 of the receptacle, showing the disposition of the parts of the same during the various stages of the application of the cap thereto, and

Figure 5 shows the final disposition of the 75 parts illustrated in Figures 2 to 4.

Figure 6 is an enlarged fragmentary view of one end of the receptacle.

The essence of my invention consists in the provision of a receptacle embodying the 80 same improved construction as has been submitted in my co-pending application aforesaid, but in which, in addition to the structure presented in my previous application, a slightly modified and improved cap connection is provided, in addition to the fact that this type of connection permits of the receptacle engaging the bent element at a point adjacent the cap, as well as at a point adjacent its base. 85

Thus as in my previous application the receptacle includes side walls 10, a head 11 being provided adjacent the lower edge of the side walls, and preferably forming an integral portion thereof, it being noted that 90 the side walls adjacent their point of connection of this head, are thickened, as has been indicated by the reference numeral 12.

This receptacle may be formed in any desired manner, although I preferably utilize the method described in my co-pending application, and this container is adapted to receive primarily a film cartridge 13, including, in the usual manner, a spool presenting end flanges 14. 100

It will be seen that the head 11 is preferably thicker than the side walls 10, and that the former element is also cup shaped, so that when the cartridge is inserted within the receptacle, the lowermost flange 14 of the same will bear against the inner face of the head, as has been clearly shown in Fig- 110

ure 1, subsequent to which the side walls 10, at points adjacent the thickened portions 12 and above the lowermost flange 14 are collapsed to provide an inwardly extending ridge 15, which engages the flange 14 to thus prevent any movement of the cartridge with respect to the receptacle.

The foregoing construction and co-operation of the parts corresponds to my co-pending application, it being also noted that similar to the application referred to the side walls 10 extend to a point well above the upper flange 14 of the film cartridge 13. However, contrary to this prior construction, 10 the cap 16 is formed with a hook portion 17 adjacent its side edge, which hook portion embraces the side walls adjacent their upper edges, as in Figure 2, so that all of these parts may be initially collapsed, as in Figure 15 3, and subsequently flattened as in Figure 4 to provide a relatively thick layer of material 18, it being noted that after this operation is completed, the outwardly extending parts of the side wall and cap are bent 20 downwardly, and inwardly as in Figure 5, to also provide a thickened portion adjacent the upper side edges of the receptacle. Also 25 in this latter connection it will be seen that the side walls 10 are bent inwardly to form a ridge 20 similar to the ridge 15, and corresponding to the same in function, also in that the ridge 20 engages the inner edges of the upper flange 14 to secure the cartridge 30 13 immovable with respect to the receptacle at this point.

It will be noted that the receptacle may be formed of softened material such as

would enable a user to cut the side walls of the same with his thumb nail, or in any other suitable manner also, that the receptacle provides thickened portions 12, 18 and 19 at points adjacent those at which it receives its maximum amount of wear, due to the cutting tendency of the flanges 14.

The head 11, incident to its cup shape, enables the receptacle to be subjected to quite an amount of end thrust, without becoming jammed, and the comparative thickness of the head 11, and portions 12, 18 and 19 protects the exterior of the receptacle.

It will be understood that numerous modifications of structure might readily be resorted to without in the least departing from the scope of my claims; which are—

1. A receptacle including side walls, and end portions, said receptacle being adapted to house a cartridge having end flanges normally lying adjacent the end portions of said receptacle, and ridges forming a part of the side wall of said receptacle, said ridges being adapted to overlap and engage said elements to prevent a movement of said cartridge with respect to said receptacle.

2. A receptacle for receiving film cartridges including side walls, a head at one end of the receptacle, and a closure cap at the other end thereof, said side walls having ridges spaced from said head and cap, the spaces between said head and cap and the adjacent ridges receiving the flanges of a film cartridge for preventing longitudinal movement thereof with respect to said receptacle.

FRANCIS JAY LYNCH.
